United States Patent Office

Des. 185,947
Patented Aug. 18, 1959

185,947

NARROW WOVEN FABRIC OR SIMILAR ARTICLE

Jack Davis, New York, N.Y.

Application March 10, 1959, Serial No. 54,914

Term of patent 3½ years

(Cl. D92—1)

Fig. 1 is a top plan view of a narrow woven fabric or similar article, showing my new design; and
Fig. 2 is a side elevational view thereof.

I claim:
The ornamental design for a narrow woven fabric or similar article, substantially as shown.
